UNITED STATES PATENT OFFICE.

JOHN ED SMART, OF MUSICK, MISSOURI.

WAGON-BRAKE COUPLING.

SPECIFICATION forming part of Letters Patent No. 794,324, dated July 11, 1905.

Application filed November 17, 1904. Serial No. 233,138.

To all whom it may concern:

Be it known that I, JOHN ED SMART, a citizen of the United States, residing at Musick, in the county of Callaway and State of Missouri, have invented a new and useful Wagon-Brake Coupling, of which the following is a specification.

The invention relates to improvements in wagon-brake couplings.

10 The object of the present invention is to improve the construction of wagon-brake couplings and to provide an inexpensive and efficient device of great strength and durability designed for coupling the connecting-rod of a wagon-brake to the upwardly-extending arm of the transverse shaft for enabling the rod to be readily attached to and removed from the upwardly-extending arm when it is desired to place a wagon-body on or remove 20 it from its running-gear.

25 A further object of the invention is to provide a coupling of this character adapted to be easily and quickly operated without the use of a wrench or similar tool and capable of effectually preventing the coupling pin or pivot from accidentally releasing the parts.

With these and other objects in view the invention consists in the construction and novel combination and arrangement of parts 30 hereinafter fully described, illustrated in the accompanying drawings, and pointed out in the claims hereto appended, it being understood that various changes in the form, proportion, size, and minor details of construction within the scope of the claims may be resorted to without departing from the spirit or sacrificing any of the advantages of the invention.

40 In the drawings, Figure 1 is a perspective view of a wagon-brake coupling constructed in accordance with this invention and shown applied to a wagon. Fig. 2 is an enlarged detail sectional view taken longitudinally of the rear portion of the connecting-rod. Fig. 45 3 is a detail perspective view of the coupling-pin-operating lever.

Like numerals of reference designate corresponding parts in all the figures of the drawings.

50 1 designates the connecting-rod of a wagon-

brake, which rod extends rearwardly from the brake-operating lever 2 to the upwardly-extending arm or member 3 of the transverse shaft 4. The transverse shaft 4 is connected with the brake-beam 5 and is mounted on the 55 running-gear of the wagon in the usual manner. The brake-operating lever is mounted on one side of the wagon body or box, as clearly shown in Fig. 1 of the drawings. The rear end 6 of the connecting-rod is enlarged 60 and bifurcated to provide two spaced sides for the reception of the upper portion of the arm 3, and these sides are provided with opposite openings for the reception of a pivot or coupling-pin 7, which also passes through 65 an opening of the arm 3, whereby the connecting-rod is coupled to the upwardly-extending arm of the transverse shaft. The coupling pivot or pin, which is disposed horizontally, is provided at its outer end with a head 8, 70 which is bifurcated for the reception of a reduced end or portion 9 of a coupling-pin-operating lever 10, which extends longitudinally of the rear portion of the connecting-rod. The reduced end 9 of the coupling-pin-operating lever 10 is provided with a slot 9^a for the 75 reception of the pivot 9^b, which connects the reduced end of the coupling-pin-operating lever to the bifurcated end or head 8 of the coupling pin or pivot 7. The slot permits the necessary play of the parts when the lever is operated to move the coupling pin or pivot 7 inward or outward. The lever 10 is curved longitudinally to present a convexly-curved 80 face to the connecting-rod, and it is provided 85 between its ends with a pair of projecting ears 11, which are pivoted by a pin or rivet 12 to the connecting-rod. The coupling pin or pivot is firmly held in the openings of the bifurcated end of the connecting-rod and the up- 90 wardly-extending arm by a spring 13, interposed between the front arm of the lever and the rod. The spring, which consists of a substantially straight piece of resilient material, is secured to the inner face of the front arm 95 of the lever 10, near the front end thereof, by a suitable fastening device 14, the lever being recessed to receive the attached end of the spring. The spring has its outer end bevelled to engage the shoulder 15, which is un- 100

dercut to interlock with the spring. By this construction the fastening device is relieved of much of the strain incident to flexing the spring. The free end of the spring bears 5 against the rod and is adapted to slide thereon. When it is desired to withdraw the coupling-pin for coupling or uncoupling the connecting-rod, the front arm of the lever 10 is pressed inward against the connecting-rod, 10 and as soon as the front arm of the lever is released the spring will automatically throw the coupling pin or pivot inward and will positively maintain the same in such position.

It will be seen that the device is exceedingly 15 simple and inexpensive in construction, that it will enable the connecting-rod of a wagon-brake to be readily coupled to and uncoupled from the upwardly-extending arm of the transverse shaft without the use of a wrench 20 or similar tool, and that the coupling pin or pivot when in engagement with the upwardly-extending arm of the rock-shaft is positively held in such engagement, so that there is no liability of the parts becoming accidentally 25 uncoupled.

Having thus fully described my invention, what I claim as new, and desire to secure by Letters Patent, is—

1. A device of the class described, comprising 30 a connecting-rod having a bifurcated end adapted to receive the arm of a transverse shaft and provided with openings, a pivot slidable in the openings, and operating mech-

anism mounted on the rod for moving the coupling-pin inward and outward and for 35 holding the same in its engagement.

2. A device of the class described, comprising a connecting-rod having a bifurcated end adapted to receive the arm of a transverse shaft and provided with openings, a pivot 40 fulcrumed between its ends on the rod and connected at one arm to the coupling-pin, and a spring interposed between the rod and the other arm of the lever. 45

3. A device of the class described, comprising a bifurcated rod having openings, a pivot or pin slidable in the openings, a lever provided between its ends with ears pivoted to the rod, one end of the lever being connected 50 with the coupling-pin, and the other end being recessed at the inner face and having an undercut shoulder, and a spring secured to the inner face of the lever in the recess thereof and having its attached end beveled and 55 engaging the undercut shoulder, the other end of the spring being free and bearing against the rod.

In testimony that I claim the foregoing as my own I have hereto affixed my signature in 60 the presence of two witnesses.

JOHN ED SMART.
